UNITED STATES PATENT OFFICE.

JOSEPH F. COMEE, OF CHICAGO, ILLINOIS, ASSIGNOR TO CAMEL COMPANY, OF CHICAGO, ILLINOIS, A CORPORATION OF MAINE.

CAR-DOOR OPERATING AND LOCKING MECHANISM.

1,197,346.

Specification of Letters Patent.

Patented Sept. 5, 1916.

Application filed November 17, 1915. Serial No. 61,912.

To all whom it may concern:

Be it known that I, JOSEPH F. COMEE, a citizen of the United States, and a resident of Chicago, Cook county, Illinois, have invented certain new and useful Improvements in Car-Door Operating and Locking Mechanism, of which the following is a specification.

My invention relates to car doors and has 10 particular reference to improvements in car door operating and locking devices.

The object of my invention is to provide a combined door operating and locking device or mechanism, which shall consist of 15 but few parts, which shall be strong and durable and low in cost, and by means of which the operator can easily apply great force either to open or close the car door and without risk of destroying or injuring 20 either the door or the car.

A further object of my invention is to provide a car door operating device by means of which the door can be positively and quickly closed or partly opened and securely locked in either of said positions and which shall be free from any possibility of 25 destructive wear when in locked position.

My invention resides in a mechanism for opening, closing and locking a sliding car door, which comprises a hasp and an operating lever coöperatively arranged on the door and the car for opening and closing the door and the hasp being adapted for engagement with a locking staple on the opposite member to positively hold the door closed or partly open.

My invention also consists in a toothed rack-like hasp and a pinion mounted upon the door and the car and adapted for operative coöperation to open and close the door, the pinion forming part of a lever by means of which great force can be applied to the door and a fixed staple arranged adjacent to the pinion, which serves the double purpose of a guide for the hasp when in mesh with the pinion and for engagement with the hasp to hold the door stationary.

My invention also consists in a hasp for freight car doors which serves the double purpose of a door lock and door operator.

My invention also consists in a rack-like hasp pivotally mounted at one end on the car door, a pinion on an adjacent part of the car with which the hasp can be brought into 55 engagement means for rotating the pinion

to open or close the door, a fixed staple for engagement with the hasp to hold the door in either of two positions, said staple being adapted to guide the rack while engaged with the pinion and means for locking the 60 rack in pinion engaging or staple engaging position.

My invention also consists in the several features of construction and the combinations, arrangements and relations of parts 65 and devices by means of which I am enabled to attain the above mentioned and other objects and all as hereinafter described and particularly pointed out in the appended claims.

My invention will be more readily understood by reference to the accompanying drawings forming part of this specification, and in which:

Figure —1— is a fragmentary side elevation of a freight car equipped with a door operating mechanism embodying my invention and showing the door locked in closed position; Fig. —2— is an enlarged fragmentary view showing the door closed and the mechanism in door operating relation; Fig. —3— is a similar fragmentary view showing the door partly open and the mechanism in door operating relation; Fig. —4— is a similar fragmentary view showing the 75 door partly open and locked in such position; Fig. —5— is an enlarged sectional view on the line 5—5 of Fig. —2—; Fig. —6— is a vertical section on the line 6—6 80 of Fig. —2—; and Fig. —7— is a perspective view of the toothed hasp.

The rough usage to which freight cars and their doors are subjected and the fact that they are exposed, in use, to all kinds of weather conditions results in a warping and 95 twisting of the various car elements, particularly in wooden cars, so that although the sliding doors on freight cars usually operate easily when the car is first built and put into service they quickly reach that condition in which they bind in their ways and the door post may and often does interfere with the easy opening and closing of the door, consequently it is difficult to move the door back and forth. This difficulty in operating the door results in the rapid destruction of car doors and cars, for, when the car reaches its destination if the door cannot be easily opened, the one who desires to open it frequently uses forcible methods, 100 105

such as wedges and hammers and such like tools, destroying and breaking up the door and the adjacent parts of the car, for of course, the goods within the car must be delivered regardless of the condition of the car. In view of this situation many mechanisms have been devised for the application of force to the car door to open and close it without destructive effects, but these mechanisms, so far as I am aware, are quite complicated comprising many parts some of which in the nature of things, cannot be made substantial enough to stand the severe strains to which they are subjected in use. To overcome these difficulties I have devised the simple door operating and locking mechanism illustrated in the said drawings, and which primarily comprises a hasp which is pivotally mounted, at one end on the car door and which serves the purpose of an operating rack, and a toothed lever pivotally mounted on the door post adjacent to the door opening and adapted to engage the rack, and by means of which relatively great force can be easily applied to the door, in the direction of its movement and without any danger of destroying the door or the adjacent parts of the car. Furthermore these operating parts are permanently secured upon the car members ready for instant coöperation when it is desired to open, close or lock the door. As a further feature I make use of my operating hasp with which to lock the door both in its closed position and in a partly open position, in which latter position it is desired to hold the door locked so that the car can be ventilated.

In said drawings A represents a freight car, and B one of the sliding doors thereof, which is adapted to slide back and forth in front of the door opening C. The door is mounted at its upper end upon a rail D by means of door sheaves E, and the lower end of the door is provided with a longitudinal ledge or flange F which is received behind a guide plate G'. At the forward end of the door opening C is a door post G having an outer post or jamb H against which the forward edge of the door is adapted to abut when the door is closed. The door overlaps the adjacent part of the post G, and as cars are usually constructed, the inner face of the door and the outer face of the post G lie very closely together so that the contents of the car cannot escape at this point, and consequently, if the post G or the forward edge of the door itself warps or becomes twisted to any appreciable extent, these two parts interfere with each other and create a great deal of friction. It is the friction or interference at this particular point that my operating device is adapted to overcome and for which I have particularly devised my door operating device. Furthermore, in the

modern construction of freight cars the forward edge of the door is usually held inwardly against the door post G by means of a wedging surface which projects over the forward edge of the door and holds the door from springing outwardly when in its closed position, which springing of the door might be due either to the warped condition of the door itself or to the pressure of the contents of the car. Consequently, unless the forward edge of the door and the adjacent surface of the post freely pass each other the interference which has been explained will exist.

I provide a hasp 2 pivotally mounted at one of its ends 3 on the face of the forward part of the door so that it can swing freely, and the hasp is adapted to be swung upwardly to a substantially horizontal position to project beyond the forward edge of the door for coöperation with the locking and operating devices which are mounted upon the post H. I provide the hasp, on its lower edge, with a series of teeth 4 which constitute a rack, by means of which I am enabled to apply force either to open or close the door.

Upon the post H I mount a lever 5 on a horizontal rigid pivot 6, the lever being adapted to project close to and swing parallel with the adjacent face of the car. I provide the pivoted end of the lever with a segmental toothed pinion 7, the teeth of which are adapted to engage with the teeth on the hasp 2 when it is desired to open or close the door, and the lever and pinion are preferably integral with each other so that this operating member is exceedingly strong. Above the pinion and spaced therefrom I provide a rigid projection 8 which projects outwardly from the post H and constitutes a locking staple. This staple also forms a guide for the hasp 2 when the teeth thereof are in mesh with the pinion and the hasp is being used as a rack, as clearly illustrated in Figs. —2— and —3—. In Fig. —3— I have illustrated the relative positions of the hasp and lever which these parts occupy at the time that the door is moved to its partly open position or when the hasp and lever are arranged to begin the closing of the door. I have also provided a locking member 9 which is mounted upon the door post H to slide up and down, and is provided at its lower end with a projection 10 adapted to pass through a perforation 11 in the staple 8 and is adapted to overlie or project in front of the hasp 2 when the same is in coöoperative relation with the pinion 7. As clearly shown in the several figures, this locking member 9 is slidably mounted upon a fixed pin 12 and is provided with an elongated slot 13 to permit it to be moved entirely out of contact with the projection 8 for the purpose of permitting the movement 130

of the hasp 2 into and out of locking position.

As shown in the drawings I provide the hasp with an opening 14 adapted to receive the staple 8 and hold the door locked in its closed position, as best shown in Fig. —1—. The locking member 9 is spaced outwardly from the face of the post H sufficiently to permit the placement of the hasp on the staple 8 beneath the member 9 as best shown in Fig. —6—.

For the purpose of sealing the door in its locked position I provide a projection 15 on the outer face of the hasp 2 adjacent to its pivoted end and adapted to lie in close relation to the downwardly projecting end 16 of the locking member 9 when the hasp is in locking position, as shown in Fig. —1—, and, furthermore, I provide the lower end 10 of the locking member 9 and the projection 15 with registering openings 16 and 17 respectively, to receive a suitable sealing member 18 as shown in Fig. —1—. The sealing member illustrated is a wire, the ends of which are bared together and firmly bound within a lead seal, that is, it is the commonly used wire seal for freight cars.

For the purpose of securely mounting the hasp upon the car door I provide a steel strap 19 mounted on the face of the door and having a perforation 20 adjacent to its forward end and I provide a staple member 21 adapted to be bolted upon the strap 19 and provided at its forward end with a staple hook 22 adapted to receive the hasp, the hasp being provided with an opening 23 for mounting upon the staple hook 22. And to prevent the removal of the staple from the steel strap I provide the inner end of the staple with a hooked end 24 adapted to project beneath the strap and hold the forward end of the member 21 against removal.

The hole 23 in the end of the hasp is of sufficient size, and the corners are rounded as shown in Fig. —5—, so that the hasp can freely swing out from the car, as indicated in dotted lines, to freely pass the projection 8 as well as swing up and down for placement in its coöperative relation with the pinion and upon the locking staple. And, obviously it is free to hang straight down at times when it is not in coöperation with the pinion or with the staple 8, consequently when the hasp is free from the pinion 7 and the locking staple 8, it hangs freely down within the area of the door and does not obstruct the door opening.

In Fig. —1— I have shown the hasp in its locking position, the door being in closed position and the locking member 9 in position to hold the hasp upon the staple 8.

In Fig. —2— I have shown the hasp in its operative relation to the pinion, the locking member 9 having been moved upwardly

to permit the removal of the hasp from the staple 8, and having been dropped again to hold the hasp in proper working relation to the pinion. At such times the lever 5 is swung around to the right so that the pinion 7 will be properly engaged with the teeth of the hasp so that when the lever is swung to the left it will force the hasp to the right, and open the door. The extreme movement of the door to the right, by means of the mechanism is illustrated in Fig. —3—. If the door has been thus opened, and if it is desired that the door be locked in such partly open position the locking member 9 is again lifted and the hasp is moved from its operative relation to the pinion, and is placed upon the staple 8, the hasp being provided with a second opening 25 for this purpose, it being obvious that as soon as the hasp is freed from the pinion the lever 5 will drop to its vertical position as shown in Fig. —1—. I provide the hasp with a second projection 26 similar to the projection 15 and likewise similar to the projection 23 adapted to coöperate with the lower end 10 of the locking member 9 for sealing the car when the door is in such partly open position. The member 26 is provided with a suitable perforation to receive the sealing member, and in Fig. —1— I have shown the door partly open, the hasp locking the door in such partly open position.

As clearly illustrated in Fig. —6— the projections 15 and 26 on the hasp can move freely beneath the lower end of the projection 10 on the locking member 9 as the hasp is moved back and forth by means of the pinion 7 and lever 5. The hasp constitutes a combined door locking and operating member adapted in one position to coöperate with the operating lever for opening and closing the door, and in another position to coöperate with the fixed projection for locking the door, and at other times free to hang in such relation to the door that it cannot obstruct the door opening.

I preferably form the pivot bearing 6, upon which the lever 5 is mounted and the locking staple 8, integrally with a metallic door stop J which is rigidly bolted to, and in fact, forms a section of the door post or jamb H. This stop is provided with flanges K adapting it to be secured in position by bolts or rivets L which pass through the adjacent parts of the wooden door jamb H and the door post G and also by interior or hidden bolts or rivets M which pass through hidden flanges N, and hence the stop is held rigidly and permanently in position. To hold the door firmly in against the overlapping part of the post G, when in closed position, I provide a laterally extending projection P forming part of the stop J and overlapping the door space, the inner surface of this projection is inclined relatively 130

to the door and is adapted to force the forward edge of the door inwardly against the outer surface of the post G. To brace the stop J against the pressure which is applied to the projection P when the door is closed I provide a rearwardly extending projection R on the stop J adapted to rest upon the adjacent surface of the car and brace the stop J against the tipping pressure applied to the projection P.

A further advantageous feature of my invention resides in the fact that the pinion 7 is only in mesh with the hasp during the operation of opening and closing the door, 15 and at all other times hangs free on its pivot, consequently there is no undue wear upon the teeth of the pinion or the hasp which might result from the constant vibration of these parts were they in mesh all 20 the time the door is closed.

A further important feature of my invention is that the hasp is free to be entered sidewise into engagement with the pinion in any relation relatively thereto; in other 25 words it is not necessary to guide the hasp into engagement with the pinion as the door is being closed. Usually the door in closing, slides very easily until its forward edge strikes the overlapping door post, then the 30 hasp is swung up from its free vertical hanging position, it is also swung out to pass the operating lever and is then entered sidewise into engagement with the teeth of the pinion and beneath the locking staple. 35 In this operation it is very easy to hold the operating lever at such an angle that the rack and pinion will be properly engaged to permit a complete closing of the door without the necessity of freeing the rack. 40 From the pinion and reengaging them in a different relation or, on the other hand, it is very convenient to reengage the lever with the pinion in such relation that a maximum pull can be most easily applied to the lever. 45 For instance, it might occur that it would be best to reengage the pinion with the hasp several times during the door-moving operation so as to keep the lever as nearly horizontal as possible. But should such reengagement be necessary or desirable it can be very quickly and easily accomplished as the hasp is free to be swung out and in for such purpose. Having engaged the rack with the pinion the locking member may be 50 inserted through the locking staple and its lower end holds the hasp from working sidewise out of engagement with the pinion during the door closing or moving operation. The door having been forced tightly 55 against the door post or jamb the locking member is withdrawn, and the hasp is swung sidewise out of engagement with the pinion and is entered upon the locking staple then the lower end of the locking member is inserted through the locking staple to hold the 60 65

hasp on the latter and thereafter the locking member can readily be sealed against withdrawal by the insertion of the seal through the locking member and the registering opening in the adjacent projection on the 70 hasp.

As many modifications of my invention will readily suggest themselves to one skilled in the art I do not limit or confine my invention to the specific structures herein 75 shown and described.

I claim:

1. In a freight car having a sliding door, a door operating and locking mechanism comprising, a toothed hasp pivotally mounted on one of said members to swing freely from one of its ends, a cooperative pinion mounted upon the other member for engagement with the hasp to open and close the door, means for rotating the pinion, a 85 fixed projection spaced from the pinion and adapted to guide the hasp while in engagement with the pinion, said hasp having an opening adapting it to be engaged with said projection to hold the door against movement.

2. In a freight car having a sliding door, a door operating and locking mechanism comprising a rack-like hasp pivotally mounted on one of said members to swing freely from one of its ends, a cooperative pinion mounted upon the other member for engagement with the hasp to open and close the door, means for rotating the pinion, means for guiding the hasp while in engagement with the pinion, said hasp formed for interlocking engagement with a staple fixed 95 on the car, when out of engagement with the pinion, to hold the door against movement.

3. In a freight car having a sliding door, a door operating and locking mechanism comprising a hasp pivoted to the door adjacent to the forward edge to swing freely from one end, a toothed rack formed on one edge of the hasp, a toothed operating lever mounted on the adjacent door post for engaging said hasp to open and close the door, a fixed projection adjacent to the toothed end of the lever adapted to guide the hasp when in engagement with the toothed lever, and said hasp provided with an opening adapted to receive the said fixed projection when the hasp is disengaged from the toothed lever to hold the door against movement.

4. In a freight car having a sliding door, a toothed lever pivotally mounted on the forward door post, a rack-like hasp pivotally mounted at one of its ends on the door adjacent to its forward edge and adapted to hang freely from said pivoted end when the door is open and the hasp is free of the toothed lever and to be engaged with the toothed lever for opening and closing the door, a fixed projection extending outwardly 130

from the said door post adjacent to the toothed end of the lever and spaced therefrom to receive the hasp between the fixed projection and lever and to guide the hasp in its back and forth movement, said hasp being free to enter sidewise into engagement with the lever.

5. In a freight car having a sliding door, a toothed lever pivotally mounted on the forward door post, a toothed hasp pivotally mounted at one of its ends on the door adjacent to its forward edge and adapted to engage the toothed lever for opening and closing the door, a fixed projection extending outwardly from the said door post adjacent to the toothed end of the lever and spaced therefrom to receive the hasp between the projection and lever and to guide the hasp in its back and forth movement, said hasp being free to enter sidewise into engagement with the lever and provided with an opening to receive the fixed projection for holding the door against movement.

6. A mechanism for moving a sliding car door relatively to a car body and comprising a relatively short rack-like hasp adapted to be pivotally mounted on one of said members to hang freely from one of its ends, means for so mounting the hasp, an operating pinion mounted upon the other member for engagement with the hasp for opening and closing the door, a fixed projection on said other member for guiding the hasp when engaged with the pinion, said hasp being adapted to swing sidewise into engagement with the pinion and means for securing the hasp to the opposite member to prevent movement of the door.

7. A freight car and its sliding door in combination with a mechanism for opening and closing the door and locking same comprising a rack-like hasp pivotally mounted at one of its ends upon the door adjacent to the forward edge, an operating pinion mounted upon the forward door post for engagement with the hasp to open and close the door, a fixed projection on the door post adjacent to the pinion for guiding the hasp in its back and forth movement, said hasp being adapted to be swung sidewise beneath the said projection into engagement with the pinion, and provided with an opening for engagement with said projection to hold the door against movement, said hasp being out of engagement with the pinion when in locking position, and a locking member adapted to project through said projection for holding the hasp in operative relation to the pinion.

8. A freight car and its sliding door in combination with a mechanism for opening and closing the door and locking same comprising a rack-like hasp pivotally mounted at one of its ends upon the door adjacent to its forward edge, an operating pinion

mounted upon the forward door post for engagement with the rack to open and close the door, a fixed projection on the door post adjacent to the pinion for guiding the rack in its back and forth movement, said rack being adapted to be swung sidewise beneath the said projection into engagement with the pinion, and provided with an opening for engagement with said projection to hold the door against movement, said rack being out of engagement with the pinion when in locking position, and a sliding bolt arranged substantially at right angles to the hasp when in operative relation to the pinion and adapted to extend through said projection for holding the hasp in engagement with the pinion.

9. A freight car and its sliding door in combination with a mechanism for opening and closing the door and locking same comprising a rack-like hasp pivotally mounted at one of its ends upon the door adjacent to its forward edge, an operating pinion mounted upon the forward door post for engagement with the hasp to open and close the door, a fixed projection on the door post adjacent to the pinion for guiding the hasp in its back and forth movement, said hasp being adapted to be swung sidewise beneath the said projection into engagement with the pinion, and provided with an opening for engagement with said projection to hold the door against movement, a locking member adapted to extend through said projection for holding the hasp in engagement with the pinion and for holding the hasp on said projection, said locking member being adapted to project in front of the hasp when the hasp is in locking position, and a rigid projection on said hasp adapted to operate with said locking member for receiving a car seal to prevent the withdrawal of the locking member from said projection.

10. A freight car and its sliding door in combination with a mechanism for opening and closing the door and locking same comprising a rack-like hasp pivotally mounted at one of its ends upon the door adjacent to its forward edge, an operating pinion mounted upon the forward door post for engagement with the hasp to open and close the door, a fixed projection on the door post adjacent to the pinion for guiding the hasp in its back and forth movement, said hasp being adapted to be swung sidewise into operative engagement with the pinion and between the pinion and the said projection, and provided with an opening for engagement with said projection to hold the door against movement, a locking member adapted to project through said projection for holding the hasp in engagement with the pinion and for holding the hasp on said projection, said hasp having two sealing projections, one arranged adjacent to each

end and each adapted to coöperate with said locking member for sealing the door in closed position and in partly open position respectively.

5 11. In a freight car having a sliding door, a pinion rotatably mounted on the car adjacent to the door opening, means for rotating the pinion, a toothed hasp for engagement with the pinion pivotally mounted at 10 one end on the door and adapted to hang freely from its pivoted end when free from the pinion, a fixed projection on the car adjacent to the pinion for guiding the hasp when engaged with the pinion, the hasp being freely movable sidewise between the projection and pinion into and out of engagement with the latter, said hasp having an opening adapted to receive said projection for locking the door against movement, 15 and the hasp being free of the pinion when in locking position.

12. In a freight car having a sliding door, an operative pinion mounted on the forward door post; a toothed hasp carried by the door adapted for engagement with the pinion when the door is nearly closed, a locking member carried by the said door post, said hasp and locking member being adapted for interlocking engagement to prevent the back and forth movement of the door, and means for holding the hasp in locking position.

13. A mechanism for moving a car door relatively to a car body and adapted to lock the door relatively to the car body and comprising, an operating pinion mounted on one said member, a lever fixed on said pinion 20 by which the latter is rotated, a toothed rack for engagement with said pinion carried by said other member and mounted thereon to hang freely from one end and adapted to be entered sidewise into engage-

ment with the pinion, whereby the lever can be placed in the first and dangerous relative position for operating, and means for locking said hasp to the opposite member to hold the door against movement, the hasp being free of the pinion when in locking position.

14. In a freight car door operating mechanism, an operating pinion adapted to be rotatably mounted on the forward door post 50 of a car, means for rotating the pinion, a toothed rack for engagement with the pinion adapted to be pivotally mounted on the car door to swing freely from one end, guide means adapted to be fixed adjacent to the 55 pinion for guiding the rack while in engagement therewith, and said rack being freely movable sidewise on its pivoted end into and out of operating position between the pinion and said projection. 69

15. In a freight car door operating mechanism, an operating pinion adapted to be rotatably mounted on the forward door post of a car, means for rotating the pinion, a toothed rack for engagement with the pinion 65 adapted to be pivotally mounted on the car door to swing freely from one end, guide means adapted to be fixed adjacent to the pinion for guiding the rack while in engagement therewith, said rack being freely movable sidewise on its pivoted end into and out of operating position between the pinion and said projection, and freely removable means for holding the rack against sidewise movement when in engagement with the 70 pinion. 75

In testimony whereof, I have hereunto set my hand this 13th day of November, 1915, in the presence of one subscribing witness.

JOSEPH F. COOPER,
